CLAIM

The ornamental design for a universal automotive wheel, as shown and described.

DESCRIPTION

FIG. 1 is a front perspective view of a universal automotive wheel showing my new design;

FIG. 2 is a first side view thereof;

FIG. 3 is a second side view thereof;

FIG. 4 is a front elevation view thereof;

FIG. 5 is a second elevation view thereof;

FIG. 6 is a third elevation view thereof;

FIG. 7 is a fourth elevation view thereof;

FIG. 8 is an alternative front respective view thereof;

FIG. 9 is a first side view thereof;

FIG. 10 is a second side view thereof;

FIG. 11 is a front elevation view thereof;

FIG. 12 is a second elevation view thereof;

FIG. 13 is a third elevation view thereof; and,

FIG. 14 is a fourth elevation view thereof.

The broken lines shown in FIGS. 1-14 are for the purpose of illustrating environment only and form no part of the claimed design.
